CLAIM

The ornamental design for an infusion pump, as shown and described.

DESCRIPTION

FIG. 1 is a top front perspective view of an infusion pump showing our new design;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is another side view thereof.

In the Figures, the dash-dot broken lines represent a boundary that forms no part of the claimed design. The even broken lines represent portions of the infusion pump and form no part of the claimed design.
